UNITED STATES PATENT OFFICE.

JOHN E. REPLOGLE, OF CLEVELAND, OHIO.

SAFETY-POCKET FOR GARMENTS.

SPECIFICATION forming part of Letters Patent No. 469,721, dated March 1, 1892.

Application filed March 27, 1891. Serial No. 386,621. (No model.)

To all whom it may concern:

Be it known that I, JOHN E. REPLOGLE, a citizen of the United States, residing at Cleveland, in the county of Cuyahoga and State of Ohio, have invented certain new and useful Improvements in Safety-Pockets for Garments, of which the following is a full, clear, and exact description, reference being had to the accompanying drawings, that will enable others skilled in the art to which my invention pertains to make and use the same.

My invention consists in the matters hereinafter described, and referred to in the pending claim.

15 In the accompanying drawings I have shown my invention in the best form now known to me; but obvious changes in the details might be made within the skill of a good mechanic without departing from the spirit of my invention, as set forth in the claim at the end of this specification.

In the drawings, Figure 1 is a side elevation of the base or main portion of my clasp. Fig. 2 is a similar view of the swinging loop 25 detached. Fig. 3 is a view partly in section on the line 3 3 of Fig. 1, showing the loop in the position assumed when the pocket is opened. Fig. 4 is a perspective view of a portion of a garment having a pocket that is provided with my spring-clasp, the pocket being shown in the opened position. Fig. 5 is a similar view of the same with the pocket closed. Fig. 6 is a vertical sectional view of the mouth of the pocket shown in the opened 35 position.

The frame or base A of the clasp consists of a U-shaped flat plate, preferably stamped out of sheet-brass, and is rolled or flanged at its edges a to stiffen it. At the extremity of 40 each leg A' is a notch a', the metal at each side of the notch being turned up to form ears b, between which the legs of the loop B are mounted on pivots b'. Flat steel springs C are secured to the back of the legs of the 45 frame, their free ends covering the back of the notches in such position as to bear against the ends of the loop. These ends of the loop b² are enlarged and squared, so as to present

flat bearing-surfaces to the springs, as shown in Fig. 3. When the loop is up and the pocket 50 is closed, the springs bear against the lower side of the loop ends and hold it closed, but yield to allow the loop to be swung down to the opening position, when they will bear against the ends of the loop-legs to hold the 55 pocket open, as will be readily understood.

The clasp is especially designed for use in connection with "change" or ticket pockets in men's coats; but it may be used with good effect in other garments. Figs. 4, 5, and 6 60 clearly show this special application, the section of garment preferably representing the flap or edge of a coat or overcoat with a change pocket. The frame or base of the clasp is firmly attached to the garment between the 65 outer fabric D and the lining d, the ends of its legs A projecting through apertures in the cloth to the outside. The wire loop B, which is pivoted between the lugs b of the frame is sewed or otherwise attached to the 70 edge of the pocket-flap E, preferably between the lining and the outer fabric of the flap, so as not to be conspicuous when the flap is down and the pocket opened. The pocket-lining or pocket proper is represented by f, 75 and this lining may constitute the inner lining or facing of the flap, as shown in Figs. 4 and 6.

I have shown my guard-flap as being connected to the outside of the pocket and folding up against the coat to close the pocket; but it might be applied to the ordinary flaps that fold down over the edge of the pocket to close it in the usual way, the spring-clasp holding it against accidentally opening. 80 85

Having thus described my invention, what I claim, and desire to secure by Letters Patent, is—

The herein-described safety-pocket clasp, comprising a flat U-shaped plate adapted to 90 be secured between the lining and outer fabric, said plate having stiffening-flanges a and the ears b at the extremity of each flange, said plate being provided at the end of each of its legs with a notch, a loop, as B, pivotally secured between the ears b and resting 95

when closed in the groove formed by the flanges and having squared portions extending through the notches in the legs of the plate, and leaf-springs secured to the flat plate and bearing against the squared portions of the ends of the loop, substantially as described.

In testimony whereof I have hereunto set my hand and seal, this 23d day of March, 1891, at Cleveland, Ohio.

JNO. E. REPLOGLE. [L. S.]

In presence of—

W.M. A. SKINKLE,
D. BROMLEY.
